UNITED STATES PATENT OFFICE.

ADDISON T. SMITH, OF CAMBRIDGE, OHIO.

ATTACHMENT FOR BATH-TUBS.

SPECIFICATION forming part of Letters Patent No. 642,168, dated January 30, 1900.

Application filed June 15, 1899. Serial No. 720,616. (No model.)

To all whom it may concern:

Be it known that I, ADDISON T. SMITH, a citizen of the United States, residing at Cambridge, in the county of Guernsey and State 5 of Ohio, have invented certain new and useful Improvements in Attachments for Bath-Tubs, &c.; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 This invention relates to attachments for bath-tubs and the like and is directed more particularly to the production of an improved support adapted for use as a seat for the bather and also as a holder for a bowl, basin, 20 or like vessel, the support to this end being constructed to be positioned whereby it may be brought below the edge of the tub when used as a seat or inverted to bring it above 25 said edge when employed to hold a vessel, the support in either position being also available 30 as a holder for articles of apparel or the bath, as will be readily understood. The nature of my invention will be readily comprehended by reference to the following detailed description and to the accompanying drawings, in which—

Figure 1 is a perspective view of my improved support in position for use as a seat for the bather. Fig. 2 is a perspective view 35 of the support in inverted position for use as a bowl or basin stand.

Referring to the said drawings by letter, A denotes my improved support, and B is one form of bath-tub to which the support is 40 adapted for application. The support comprises a shelf *a*, preferably rectangular in shape, but having rounded corners, which shelf may be of any suitable material. One side of the shelf may be plain, as shown, or 45 so formed as to provide a comfortable seat for the bather, but the opposite side is preferably provided with a depression *a'* to receive the base of the vessel.

The arms *c c* of the support may be of any 50 suitable material, preferably metal. For economy of construction I employ stout wire for these arms, the arms proper being ex-

tensions of lengths of wire secured to that side of the shelf which forms the support for the bowl or basin. Each of the lengths is 55 secured to said side by staples *d*, the wire being offset at the depression to prevent the wire, and consequently the legs, from movement. The wire beyond the shelf is bent upwardly to form the arms, and each of said 60 arms, there being four in number, is provided at its end with bends, providing opposite hook portions *c' c²*, the hook portions *c'* engaging the edges *b* of the tub when the shelf is in the position shown in Fig. 1, while 65 the hook portions *c²* engage said tub edges when the shelf is in the inverted position. (Shown in Fig. 2.) The length of the arms is such that when suspended within the tub the shelf will be at the proper height to afford 70 a comfortable seat for the bather, and when in inverted position the length of the legs brings the shelf above the edge of the tub, so that the supported basin or bowl may be within 75 easy access of the user. The hook portions *c' c²* will conform to the edges of the particular tub for which they are designed as an attachment, and the dimensions of the shelf will be proportionate to the width of the tub, although if found desirable the legs may be 80 bent outwardly or inwardly to conform to varying widths of tubs. In either of the positions shown the shelf affords a support for wearing-apparel, articles of the bath, &c.

My improved support is very simple in construction, and hence can be cheaply produced. 85 The simplicity of construction likewise precludes disorder, and by the construction employed the support is efficient and is readily converted from a seat into a stand for bowls 90 or other vessels.

I claim as my invention—

1. An attachment for bath-tubs and the like, comprising an invertible shelf provided with supporting-arms each arm having at its 95 end the double hook portions *c' c²* oppositely disposed and conforming to and adapted to hook over the edge of the tub or the like, whereby the shelf may be securely positioned below the edge to afford a seat, or securely 100 placed in inverted position above the edge to afford a stand for a bowl or other vessel.

2. An attachment for bath-tubs and the like, comprising a shelf having a depression

in one of its sides to receive the base of a bowl or other vessel, supporting-legs for the shelf formed of wire having the offsets as described the legs at their ends being provided with oppositely-disposed hook portions adapted to rest on the edge of the tub and to engage the sides of said edge to prevent transverse movement whereby the shelf may be positioned below the edge to afford a seat or inverted to

bring it above the edge to afford a stand for a bowl or other vessel.

In testimony whereof I affix my signature in presence of two witnesses.

ADDISON T. SMITH.
